United States Patent

Des. 235,650
Patented July 1, 1975

235,650

MODEL OF A BIRTH CANAL

Karen A. Haddad, 352 W. Woodland,
Ferndale, Mich. 48220

Filed Apr. 16, 1973, Ser. No. 351,466

Term of patent 14 years

Int. Cl. D19—07

U.S. Cl. D10—62

FIG. 1 is a perspective view of a model of a birth canal embodying my new design;

FIG. 2 is a top plan view thereof;

FIG. 3 is a bottom plan view thereof;

FIG. 4 is a front elevational view thereof;

FIG. 5 is a rear elevational view thereof; and

FIG. 6 is a left-side elevational view thereof.

I claim:

The ornamental design for a model of a birth canal, as shown and described.
